CARBURETOR

Walter H. Weber, Detroit, Mich., assignor to Detroit Lubricator Company, Detroit, Mich., a corporation of Michigan

Application May 22, 1939, Serial No. 274,882

5 Claims. (Cl. 261—34)

My invention relates to new and useful improvements in carburetors and more particularly to a carburetor for supplying fuel mixture for an internal combustion engine.

An object of my invention is to provide a carburetor which is operable to lift fuel from a low lever supply tank, thereby eliminating the necessity for the usual vacuum tank or fuel feeding pump.

Another object is to provide a carburetor in which the fuel and air supplied to the engine will be uniformly mixed.

Another object is to provide means to supply supplemental fuel for acceleration.

Another object is to provide means for increasing the ratio of fuel to air for engine starting and for cold engine operation.

The invention consists in the improved construction and combination of parts, to be more fully described hereinafter and the novelty of which will be particularly pointed out and distinctly claimed.

In the accompanying drawing, to be taken as a part of this specification, I have fully and clearly illustrated a preferred embodiment of my invention, in which drawing—

Figure 1 is a view in vertical central section of a carburetor showing my invention, and

Fig. 2 is a top plan view of the carburetor of Fig. 1 but having the air inlet valve broken away to show the internal construction.

Referring to the drawing by characters of reference, 1 designates generally the carburetor casing having a vertical passageway therethrough with an open upper end portion 2 providing an air inlet chamber 3. Opening downward from the chamber 3 eccentrically thereof, there is a mixing chamber 4 which discharges through a throttle body member 5 having a flange 6 by which the carburetor may be secured to the inlet manifold of the engine. Within the throttle body member 5 there is a butterfly type throttle valve 7 rotatably supported by a throttle shaft 8. Positioned at one side of the mixing chamber 4 there is a vertically extending cylindrical dash-pot and pump chamber 9 which is eccentric of but directly beneath the air inlet 3. The chamber 9 is separated from the air inlet 3 by a horizontally extending wall 10 which has therein a cylindrical recess 11 opening downward into and concentrically with the chamber 9. A guideway 12 extends concentrically from the upper end of the recess 11 through the wall 10 to the air inlet 3. Reciprocally guided and fitting in the guideway 12 there is a valve stem 13 which ex-

tends at its upper end into the inlet 3 and has pivotally secured thereto a link 14. Within the air inlet 3 and controlling admission of air to the mixing chamber 4, there is a suction responsive air valve plate 15 which is eccentrically mounted on a shaft 16 to swing downward across the entrance to the mixing chamber 4. The link 14 is pivotally secured to a bracket 17 secured to the underside of the plate 15 on the opposite side of shaft 16 from the chamber 4 so that the valve stem 13 will be lifted on opening movement of the air valve. A supporting member 18 projects from the wall 10 into the mixing chamber 4 and has a vertical bore 19 therethrough concentric with the longitudinal axis of the mixing chamber. Tightly fitting and secured within the bore 19 there is a nozzle member 20 which extends downward therefrom. The nozzle member 20 has a converging-diverging Venturi-like bore providing a throat 21 positioned within the length of bore 19. The throat preferably comprises a short downward flaring portion of greater included angle than the diverging discharge portion 22 of the nozzle member so that the throat entrance from the converging air inlet portion 23 of the bore will be the most restricted portion of the nozzle bore. Supported by the casing 1 there is a float chamber member 24 having a constant level reservoir 25 with a fuel inlet 26 from the usual supply tank. The inlet 26 is controlled by the usual float operated valve mechanism 27 which serves to maintain the liquid level substantially constant at say the line L—L. The reservoir 25 is provided with a calibrated air inlet 28 from atmosphere, the reservoir being otherwise sealed against air admission. A fuel supply conduit 29 leads from the bottom of the float chamber into the lower end of the dash-pot chamber 9. Reciprocal in the wall recess 11 there is a tubular valve port member 30 having at its upper end a restricted portion 31 providing a valve port. The lower end portion 32 of member 30 is of enlarged internal diameter and extends downward into the chamber 9. The upper portion of member 30 is provided with an external rack cooperable with a pinion 33 for reciprocating the member 30. Reciprocally fitting within the tubular portion 32, there is a sleeve member 33a having a flange 34 at its lower end on which seats an annular cup-shaped piston 35. The tubular valve port member 30 is urged upward and the piston 35 is opposed in upward movement by a helical coil spring 36 which surrounds the sleeve member 33a and the lower tubular portion 32 and which abuts

a spring seat member 37 secured to and extending laterally from the portion 32. Intermediate the ends of the valve stem 13 there is a metering valve 38 cooperable with and extending through the port 31. The lower end portion of the stem 13 is secured as by a cross pin 39 in a spider 40 rigidly fixed within the sleeve member 33. Leading from the recess 11 at its upper end and on the outlet side of port 31 there is a fuel conduit 41 which opens into the bore 19 for communication with a calibrated orifice 42 which opens into the throat 21. A vapor conveying conduit 43 for gas and air extends through the wall 10 from the reservoir 25 above the liquid level therein. The conduit 43 has a calibrated opening 44 into the reservoir 25 which is proportioned relative to the calibration of the atmospheric bleed 28 so as to control the sub-atmospheric pressure or depression over the liquid in the reservoir. The other end of conduit 43 opens into the bore 18 above the conduit 41 and communicates with a calibrated orifice 45 which opens into the throat 21 directly above and on the air inlet side of the orifice 42 so that any discharge from the orifice 45 will pass directly over and across the outlet of orifice 42. The conduit 43 communicates through a supplemental fuel conduit 46 with the dash-pot chamber 8 but out of direct communication with the main fuel conduit through the sleeve 33^a and portion 32; that is, the conduit 46 opens into the annular pump chamber above the piston 35 and surrounding the lower end portion of the valve port member 30. The conduit 46 is provided with a downward seating ball check valve 47 having sufficient weight to hold the conduit 46 closed against discharge of fuel by suction in the conduit 43.

The operation of this carburetor is as follows: When starting a cold engine, the pinion 33 will be rotated to move the port member 30 downward against the force of spring 36, thereby increasing the opening of the port 31. This adjustment will increase the resistance to opening movement of air valve 15 by increasing the compression on the spring 36, thereby reducing the air supplied for a given sub-atmospheric pressure in the mixing chamber 4 and will also increase the effective flow area of the fuel supply conduit through orifice 42 to further increase the ratio of fuel to air for all positions of the air valve 15. When the engine has fired and is running under its own power, the pinion 33 will be rotated to return the valve port member 30 toward normal operating position and completely to normal position when the engine is thoroughly warmed up. The sub-atmospheric pressure in the mixing chamber 4 will not only act on orifice 42 to draw fuel from the reservoir 25 but will also act through conduit 43 to reduce the pressure over the liquid in the reservoir so that fuel will be lifted from the supply tank and drawn into the reservoir when the float mechanism opens the inlet passageway 26. The air and gas drawn into the throat 21 through orifice 45 will discharge directly over the fuel orifice 42, thereby aiding the feeding of fuel into the nozzle member by aspirating action. This air and gas will also be discharging directly into the fuel from orifice 42 due to the throat flare and the main air stream passing the throat so that the liquid fuel will be broken up and intimately mixed with the air in the nozzle member. The air bleed 28 provides a differential of pressure above and below the fuel so that fuel will feed through the port or orifice 42. During idling operation of 75

the engine the air valve 15 will remain in substantially closed position so that the nozzle member 20 will have very little boosting effect by Venturi action. As the throttle 7 is opened, 5 increasing the sub-atmospheric pressure in the mixing chamber 4 and on the outlet side of air valve 15, the valve 15 will move toward open position in accordance with the sub-atmospheric pressure and the resistance afforded by the spring 36 and will lift the fuel metering valve relative to port 31 to increase the fuel supplied relative to the increased supply of air. As the air valve moves toward open position, increasing the rate of air flow through the carburetor, the nozzle member 20 will become effective to boost the suction over the liquid in the reservoir on the fuel orifice 42. If the throttle valve 7 is moved quickly toward open position for engine acceleration, the fuel in the annular pump chamber will be compressed by the piston 35 and be discharged through conduit 46 into the vapor conveying conduit 43 and thence be discharged through orifice 45 into the bore of nozzle member 20, thus providing the necessary enriched mixture for quick acceleration.

By positioning the nozzle member 20 on the outlet side of air valve 15 such that the air valve controls the air supply to the nozzle member inlet 23, the disadvantage of frost forming in 30 the throat of the nozzle member is eliminated. The formation of frost in the throat of a nozzle member which passes or supplies substantially all of the air for low speed or engine idling operation will obstruct the fuel orifice and seriously impair carburetor operation. The high air velocity through the nozzle member at low engine speeds is avoided by my construction wherein only a portion of the air at low speeds passes through the nozzle member, the remaining air 40 passing around the nozzle member and mixing with the fuel discharging from the nozzle member.

It will be apparent that this carburetor can also be used as a gravity feed carburetor or one 45 having the float chamber fed by means of a vacuum tank or fuel pump. If it is desired to so utilize the carburetor, it is only necessary to increase the size of bleed 28 so that substantially atmospheric air will exist over the fuel in the reservoir 25.

What I claim and desire to secure by Letters Patent of the United States is:

1. A carburetor comprising, a casing having a passageway therethrough with an air inlet and 55 a fuel mixture outlet, a nozzle member having a converging-diverging bore providing a throat, said bore having one end open for air admission and having its other end discharging into said passageway, a fuel reservoir, a fuel supply conduit leading from said reservoir and discharging into said bore at said throat, a vapor conveying conduit leading from said reservoir above the liquid level therein, and discharging into said bore at said throat, the point of discharge of 60 said fuel conduit being substantially at the point of low pressure in the discharge path of vapor from said vapor conduit, the opening of said vapor conduit into said bore being on the air admission side of and closely adjacent the opening of said fuel conduit into said bore so that the vapor is discharged across the fuel conduit opening to increase the suction effect on said fuel opening and to thoroughly blend the vapor and fuel in said bore, a supplemental fuel supply 65 conduit leading from said fuel conduit into said

vapor conduit, and means to control the discharge of fuel through said supplemental conduit to said bore.

2. A carburetor comprising, a casing having a passageway therethrough with an air inlet and a fuel mixture outlet, a nozzle member having a converging-diverging bore providing a throat, said bore having one end open for air admission and having its other end discharging into said passageway, a fuel reservoir, a fuel supply conduit leading from said reservoir and discharging into said bore at said throat, a vapor conveying conduit leading from said reservoir above the liquid level therein and discharging into said bore at said throat, the point of discharge of said fuel conduit being substantially at the point of low pressure in the discharge path of vapor from said vapor conduit, the opening of said vapor conduit into said bore being on the air admission side of and closely adjacent the opening of said fuel conduit into said bore so that the vapor is discharged across the fuel conduit opening to increase the suction effect on said fuel opening and to thoroughly blend the vapor and fuel in said bore, a supplemental fuel supply conduit leading from said fuel conduit into said vapor conduit, a pump operable to discharge fuel through said supplemental conduit to said bore, and an automatic valve in and closing said supplemental conduit against feeding of fuel by pressure reduction in said vapor conduit.

3. A down-draft fuel-lifting carburetor comprising, a casing having an open-ended passageway therethrough with an air inlet at its upper end and a fuel mixture outlet at its lower end, an eccentrically mounted valve plate in said air inlet and responsive to suction in said passageway, said valve plate being cooperable with said air inlet upon movement to admit air to said passageway along its peripheral surface, a downward discharging nozzle member positioned within and extending longitudinally of and spaced from the side walls of said passageway on the outlet side of said valve plate, said nozzle member having an open-ended converging-diverging bore providing a throat, a fuel reservoir, a vapor conveying conduit leading from said reservoir above the liquid level therein and opening laterally into said throat, a fuel conveying conduit leading from said reservoir below the liquid level therein and opening laterally into said throat closely adjacent to and below the opening of said vapor conduit, a pump chamber in said fuel conduit, a tubular valve port member reciprocally fitting in said fuel conduit and having a portion extending into said pump chamber, a sleeve member in said pump chamber and reciprocally fitting said extending portion, a piston carried by said sleeve member and fitting said chamber, a fuel metering rod extending through said port member and interconnecting said valve plate and said sleeve member, a helical coil spring surrounding said sleeve member and interposed between said tubular member and said piston to

oppose movement of said piston and said valve plate, and means to adjust said port member to regulate the effective flow area of said fuel conduit.

- 5 4. A down-draft carburetor comprising, a casing having a tubular air inlet portion at its upper end, a mixing chamber passageway and a dash-pot chamber having substantially parallel longitudinal axes, said mixing chamber passageway opening downward from and eccentric of said inlet portion, said dash-pot chamber being positioned besides said mixing chamber passageway and directly below said inlet portion, a laterally extending wall in said casing separating said dash-pot chamber from said inlet portion and having an elongated recess opening into said dash-pot chamber, said wall having a guideway extending concentrically from said recess and opening into said inlet portion, the longitudinal axes of said recess and said guideway being substantially parallel to the axes of said mixing chamber passageway and said dash-pot chamber, a valve stem extending through said guideway into said dash-pot chamber and said inlet portion and having a metering valve intermediate its ends, an eccentrically mounted valve plate in said inlet portion and connected to said stem, an open-ended downwardly discharging nozzle member extending longitudinally of and spaced from the walls of said passageway and supported by said wall, the longitudinal axis of said nozzle member being substantially parallel to the axis of said guideway, a fuel conduit leading from said recess into said nozzle member, a piston in said dash-pot chamber and connected to said valve stem, a valve port member in said recess and surrounding said metering valve, and means to supply fuel to said dash-pot chamber.
- 10 5. A carburetor comprising, a casing having a passageway therethrough with an air inlet and a fuel mixture outlet, a nozzle member having a converging-diverging bore providing a throat, said bore having one end open for air admission and having its other end discharging into said passageway, a fuel reservoir, a fuel supply conduit leading from said reservoir and discharging into said bore at said throat, means to supply a gas to said reservoir, a gas and vapor conveying conduit leading from said reservoir above the liquid level therein and discharging into said bore at said throat, the longitudinal axis of said vapor conduit being at an angle relative to the longitudinal axis of said fuel conduit, said axes intersecting within said bore closely adjacent the opening of said fuel conduit into said bore, the opening of said vapor conduit into said bore being on the air admission side of and closely adjacent the opening of said fuel conduit into said bore so that the gas and vapor is discharged across the fuel conduit opening to increase the suction effect on said fuel opening and to thoroughly blend the vapor and fuel in said bore.
